UNITED STATES PATENT OFFICE.

GEORGE S. BURR, OF EVERGREEN, COLORADO, ASSIGNOR OF ONE-HALF TO
JAMES BILLINGSLEY, OF BALTIMORE, MARYLAND.

BUOYANT SCREW-PROPELLER.

SPECIFICATION forming part of Letters Patent No. 333,445, dated December 29, 1885.

Application filed October 15, 1885. Serial No. 179,921. (No model.)

To all whom it may concern:

Be it known that I, GEORGE S. BURR, a citizen of the United States, residing at Evergreen, in the county of Jefferson and State of Colorado, have invented certain new and useful Improvements in Buoyant Screw-Propellers, of which the following is a specification.

My invention relates to an improvement in boats, the object being to provide a boat with a screw-propeller, which will also serve to buoy up or sustain the boat.

The invention is illustrated in the accompanying drawings, in which Figure 1 is a side view of the improved boat. Fig. 2 is a top view. Fig. 3 is an end view showing the position of the boat in the water when unloaded. Fig. 4 is a cross-section of the screw-propeller.

The boat A may be of any desired shape or construction. For the purpose of illustration the ordinary shape is here shown. A hollow tight cylinder, B, has a spiral flange, C, around it, which serves as a screw-propeller. The cylinder being light will float and gives buoyancy to the boat. The cylinder may have any desired shape at the ends—rounded, square, or tapering—somewhat cone-shaped, as shown at d in Fig. 1. The spiral flange may be secured to the cylinder in any convenient or approved manner. In the present instance one flange continues spirally around it from end to end; but two flanges may be used, if desired. At each end the cylinder has a journal, e, which sets in a bearing, f, on a metal keel-frame, G. This keel-frame G is an iron bar, whose upright ends h support the boat, while the lower longitudinal part between the said two upright ends is a kind of false keel, and serves as a ballast to prevent the craft from careening. The screw-propeller C is thus between the lower bar and the boat, and turns in its bearing f. At the stern end the journal e has a spur-wheel, i, and a shaft, L, passes through the boat, a suitable packing, k, in the boat-bottom being provided to prevent leakage, and a spur-wheel, l, on the shaft engages with the spur-wheel i on the screw-propeller. By turning the shaft L in the boat

the screw-propeller will be revolved, and thereby the craft will be moved. Any suitable contrivance may be employed in the boat to impart motion to the shaft L. In the present instance a crank, m, is fixed to the shaft. It may be driven by steam or other power. A rudder, N, is rigged at the stern and extends down the rear upright end of the false-keel bar, and a tiller, o, is fixed to the rudder-post, as usual. It will be seen that for a light boat the hollow cylinder may serve to sustain it when unloaded, as shown in Fig. 3, entirely above the water. The relative size and weight of hollow cylinder and boat may be such as, when loaded, to let the boat set lightly on the surface of the water without displacing much water. It is obvious two hollow cylinders may be thus provided with spiral flanges, and the two placed side by side and the boat wholly sustained above them. Properly constructed on this plan, a boat may be moved with great rapidity.

Instead of a hollow cylinder the cylinder may be made solid, but of some very light buoyant material, like cork, so as to have the desired buoyant properties.

Having described my invention, I claim and desire to secure by Letters Patent of the United States—

1. A boat having a false-keel bar, G, in combination with a buoyant cylinder having a spiral flange and mounted between the said false-keel bar and boat, as set forth. 80
2. A boat having in combination, a body, a false-keel bar depending below the body, a buoyant cylinder provided with a spiral flange and mounted between the body and false-keel bar, and driving mechanism, substantially as 85 described, connecting the boat-body with the buoyant cylinder, as set forth.

In testimony whereof I affix my signature in presence of two witnesses.

GEORGE S. BURR.
